(74) Attorney, Agent, or Firm — CANTOR COLBURN LLP

(57) CLAIM

The ornamental design for a outdoor flower box, as shown and described.

DESCRIPTION

1. Outdoor flower box

1.1 Perspective [Top, front and left-side]

1.2 Perspective [Top, back and right-side]

1.3 Left

1.4 Front

1.5 Back

1.6 Top

1.7 Bottom

The parts colored in white and delineated in dashed lines form no part of the claimed design; the right-side views are omitted because they are mirror images of their respective left-side views.

1 Claim, 7 Drawing Sheets
